APPLICATOR TOOL

Jesse E. Hall, Weatherford, Tex.

Application May 16, 1949, Serial No. 93,457

8 Claims. (Cl. 29—236)

1

This invention relates to improvements in an applicator and refers more particularly to a device for applying rubber protectors to drill pipe. Its principal novelty resides in the use of two splined tapered cones mounted in opposed relationship upon a mandrel in a hydraulic jack so the splines of each cone register with the slotted portions of the opposed cone, expanding a rubber annulus between the cones by moving the cones together, shifting the expanded protector to the sleeves of a collapsible hydraulically controlled transfer cage and releasing the expanded protector from the cage directly onto a section of drill pipe.

It is recognized that many different types of applicator tools have been devised but none have given the satisfaction desired for a number of different reasons some of which will be mentioned. Because of the great expansion force required apparatus has been heavy, cumbersome and difficult to handle and operate. The machines heretofore devised frequently tore the edges, defaced the surfaces or completely disrupted the protector during the expanding operation. Another objection is the delay and the time that it takes to expand the protectors and transfer them to the drill pipe causing delay in other operations on the rig.

An object, therefore, is to provide an applicator which is efficient, rapid in operation and one which reduces tearing or marring of the rubber edges or surfaces of the protector to a minimum.

Another object is to provide a portable device which may be carried and transported from place to place in a light truck or in the rear of an automobile.

A further object is to provide an applicator which can be operated by an individual and the protectors expanded and transferred from the expanding mechanism to the drill pipe almost as rapidly as the operator can engage and disengage the transfer cage from the frame.

Other and further objects will be obvious from the description which follows.

In the accompanying drawings which form a part of the specification and are to be read in conjunction therewith and in which like reference numerals indicate like parts in the various views there is shown an embodiment of the invention.

Fig. 1 is a side elevational view of the splined tapered members and hydraulic jack or frame with a protector in position to be expanded.

Fig. 2 is a side elevational view of the hydraulic jack with the transfer cage extended and positioned within the frame.

Fig. 3 is a side view of the hydraulic jack and transfer cage, the latter contracted, and a protector expanded ready to be transferred from the cage to a drill pipe,

2

Fig. 4 is a perspective view of the transfer cage on a drill pipe preparatory to releasing the protector,

Fig. 5 is a side view of a portion of the drill pipe with the protector mounted thereon,

Fig. 6 is an end view of the hydraulic jack showing the construction of the removable end plate,

Fig. 7 is a view taken along the line 7—7 in Fig. 2 in the direction of the arrows, and

Fig. 8 is a side view of the hydraulic jack and cage with parts broken away and parts in section to reveal the mounting of the splined tapered members and transfer sleeves.

The applicator is made up of four essential parts or units which include a hydraulic jack, a transfer cage, a removable slidably splined tapered member or cone and removable end plate.

Hydraulic jack

The hydraulic jack, best shown in Figs. 1, 2, 3 and 8, comprises a hydraulic cylinder 10 to which is affixed base plate 11. The hydraulic system and controls for actuating the piston have been omitted for simplicity. Extending from the base plate are a plurality of tie rods 12, which are rigidly attached at one of their ends to the base plate to form a rigid open cage or frame; at their opposite free ends are locking heads 12a formed by machining grooves in the rods a short distance from the ends. Upon the hydraulic piston 13, operating in a cylinder 10, is fixedly mounted the splined tapered member or cone 14. The forward frusto conical tapered portion of the member is slotted longitudinally to form the splines 14a. Centrally of the member is a shoulder 14b while the rear of the member has a plain surfaced taper 14c, but is not splined. This portion of the cone is internally slotted to receive the splines of the opposed cone when they are brought into registration as hereinafter explained. Piston 13 extends ahead of the splined cone 14 in the form of a cylindrical mandrel 15.

Slidable tapered member

In Figs. 1, 2, 3, 6, 7 and 8 is shown a slidable splined tapered member 16, corresponding in its general construction to member 14 in that it has the tapered splines 16a, a shoulder portion 16b, and an unsplined tapered rear portion 16c. The shoulder portion, however, of this cone is at the opposite side of the cone from the shoulder on cone 14. Tapered member 16 is centrally drilled to slidably fit on mandrel 15 and a keyway is milled within the cone to register with key 17 on mandrel 15 to prevent rotation of the cone on the mandrel. The key is located to position cone 16 so its splines are in alignment and will register with the slots of cone 14 when the two cones are moved together, as will be hereinafter described. In Figs. 1, 2, 3, and 4 there is shown

a protector 18 between the expanding cones and in Fig. 5 the protector is shown mounted upon drill pipe 19.

The transfer cage

The transfer cage used for carrying the expanded protector from the frame to the drill pipe is shown in Figs. 2, 3, 4, 7 and 8. Its construction is probably best shown in Figs. 2, 4 and 8. In brief, it comprises flanged sleeves 20 and 21 whose tapered stepped sleeve portions are designated as 20a and 21a, respectively. The flanges of both sleeves are apertured to slide freely onto rods 12, and when transfer cage is mounted thereon (see Figs. 2, 3, 7 and 8) the rods serve as guide rails to maintain the sleeves properly centered with respect to the axis of mandrel 15. It will be seen from Fig. 8 that the bore of sleeve 20 is of such size as to slide freely onto the cylindrical portion of cone member 16, and when positioned as shown its tapered exterior is, in effect, a continuation of the tapered nose portion of member 16. Similarly, sleeve 21 is adapted to slide onto the cylindrical portion of member 14 in such manner that its tapered exterior will form a continuation of the tapered nose of the cone 14; under this condition it will be understood that the shoulder 14b on member 14 seats in the complementary annular recess in the rear face of sleeve 21.

Arranged around the circumference of the flange of sleeve 20 and affixed thereto by bolts 22 are a plurality of hydraulic pistons 23 reciprocable in hydraulic cylinders 24. The flanged portion of sleeve 21 is also apertured to receive hydraulic cylinders 24, and is fixedly attached to the cylinders so the sleeve moves with them. The hydraulic system of the transfer cage is a closed system comprising the space within the cylinders 24 on opposite sides of pistons 23a, detailed in Fig. 7, connected through a series of pipes 25 at one end of the cylinders and by pipes 26 at the opposite end of the cylinders. These pipes at the opposite ends of the hydraulic cylinders are interconnected by pipes 27 and 28 through valve 29. The manner in which the pipes of this hydraulic system are connected into the hydraulic cylinders, to provide communication for the liquid to pass from one end of the cylinders to the other, is best shown in Figs. 2, 4 and 7. Surrounding the hydraulic cylinders are perforated spacer tubes 24b attached to the flange of sleeve 21 and abutting against base plate 11 to properly position the transfer cage within the hydraulic jack. Handles 30 on the edge of flange 21 facilitate handling of the cage.

The backing plate

A backing or holding plate 31 is shown removed from the frame in Fig. 3 and in end elevation in Fig. 6. This plate is apertured to receive the head portions 12a of tie rods 12. In the plate are drilled elongated holes 32 equipped with locking plates 33, the latter serving to rigidly hold the plate in position at the ends of the tie rods when their heads have been inserted in the holes and the plate rotated through an angle corresponding to the arc of the holes. To facilitate mounting of the backing plate 31 and attaching and detaching it from the ends of the tie rods there are furnished on the outer face of the plate handles 34. Slotted openings 35 in the plate accommodate the heads of bolts 22 by which the hydraulic pistons 23 are attached to the flanges of sleeves 20.

4
Operation

In operation, the hydraulic jack is lowered to a horizontal position and, with the holding plate 31, the cone 16 and the transfer cage all removed, a protector 18 is slid onto the mandrel and against the splines of cone 14. Removable cone 16 is then slid onto the mandrel with its splines facing those of cone 14, key 17 registering with the keyway within the cone and holding the cone against rotation. It will be noted that the tapered ends of the splines of the two cones now have entered the opposite ends of the protector 18 as shown in Fig. 1.

Next, turning to the transfer cage, valve 29 is opened and the sleeves 20 and 21 are manually pulled apart as far as possible, which, it will be understood, causes the hydraulic fluid in cylinders 24 to flow from the ends nearest sleeve 20 to the opposite ends of the cylinders. Closing of valve 29 will lock the sleeves in separated condition.

The transfer cage then is slid onto the guide rails 12 whereupon sleeve 21 advances over the cone member 16 and over the protector 18 to approximately the position illustrated in Figs. 2 and 8; the backing plate 31 then is mounted on and locked to the ends of the rods 12 as shown in Figs. 2, 6 and 8 so that it abuts the outer face of sleeve 20 and closes the end of the frame on which the transfer cage now is supported.

Preparatory to expanding the protector 18, valve 29 is opened so that sleeves 20 and 21 no longer are locked in separated condition. Then hydraulic fluid is introduced behind the piston in cylinder 10 by fluid pump mechanism conventional to hydraulic apparatus and omitted from the drawings. Suitable controls are used in the introduction of the fluid to control the rapidity with which the piston is actuated and the length of the thrust. As the piston 13, cone 14 and mandrel 15 move as a unit longitudinally within the elongate frame formed by the rods or rails 12 and the associated end plates 11 and 31, the splines of the respective cones will advance evenly towards each other within the protector. The cones are aligned on the mandrel so that the splines of each register with the slots of the opposed cone and the depth of the slots in the respective cones is such that the cones can be drawn together to a position where their cylindrical portions are in substantial abutment. As cone 14 moves with the piston toward this position its shoulder portion 14b seats in the recess in the outer surface of sleeve 21 causing the sleeve to move with it along the guide rails as it advances toward the other cone. Plate 31 at the opposite end of the jack abuts against the shoulder portion 16b of cone 16 holding it fixedly against longitudinal movement as cone 14 advances.

Under this condition, as has been pointed out hereinbefore, the tapered exterior of each sleeve is in effect a continuation of the tapered nose of the cone which projects beyond the end of the sleeve; or to put it differently, each cone now is disposed within its associated sleeve as an internal core, and the two parts function as a unitary, continuously tapered member wherein the large portion of the taper lies on the exterior of the sleeve and the contiguous smaller portion of the taper lies on the nose of the cone element. Thus, as the two tapered assemblies (each assembly comprising the two parts functioning as an integral unit) move toward one another protector

18 is expanded and the outer edges of the protector expand outwardly moving along the tapered surfaces of the splines and thence onto the transfer sleeves where the protector finally rests in the fully expanded condition shown in Fig. 3. As can be appreciated from this figure the adjacent ends of the sleeve 20 and 21 now are in substantial abutment midway between the ends of the protector and the protector thus is supported wholly on the tapered portion of the two sleeves, while at the same time it is compressed in an axial direction by the end flanges on the sleeves. At this time valve 29 is closed to lock the pistons 23 in retracted position within the cylinders 24 so that the sleeves 20 and 21 cannot move apart when the compressive force exerted on them by the cylinder 10 is released.

This force next is released by reversing the travel of piston 13 in cylinder 10, and then holding plate 31 is rotated to an unlocked position and removed as shown in Fig. 3. The transfer cage now can be slid off the ends of the rods 12 and carried to the drill pipe onto which it is desired to mount the protector. During this transfer operation it will be obvious that the protector in its expanded condition is under great elastic stress, the nature of which is such as to impose upon the sleeves 20 and 21 a very great force tending to urge them apart; as long as valve 29 remains closed, however, the sleeves cannot move apart and the hydraulic system of the transfer cage thus functions as a tension link between the two sleeves securing them together against the oppositely directed force exerted by the protector itself.

While in this condition the transfer cage can be advanced along the drill pipe as shown in Fig. 4 to locate the protector in desired position, and when so located valve 29 is opened to release the expanded protector and permit it to contract onto the surface of the pipe; the highly elastic force of the expanded protector snaps the sleeves apart and shifts the hydraulic fluid in cylinders 24 from one end of the cylinders to the opposite end through the hydraulic pipe system previously explained. Grease is used on the surfaces of the sleeves to reduce friction during expansion and facilitate discharge of the protector from the sleeves to the drill pipe. In its constricted condition protector 18 will grip tightly and evenly to the surface of the drill pipe as shown in Fig. 5. The cage can now be slipped off of the end of the pipe and is ready for use in expanding another protector.

It is recognized that meshing splined cones have been used in the expanding of drill pipe protectors, as shown in the patent to Harris No. 2,346,801. Transfer sleeves have also been used to shift an expanded protector from the expanding mechanism to the drill pipe, but it is believed novel in this art to utilize the meshing splined cones with transfer sleeves in the relationship shown and employing a transfer cage with buffering hydraulic cylinders.

Thus, it will be seen that there has been provided a device for expanding protector rings or rings of any sort whose inside diameter is to be enlarged to fit upon a larger object. There has been provided an applicator which requires a minimum of manual effort and one in which high expansive forces are obtained by the simple manipulation of a single hydraulic cylinder. The applicator not only provides a means for easily expanding a protector but furnishes a portable device for transferring the expanded annulus

from the expanding mechanism to the drill pipe where it is released and applied to the pipe in a safe and simple operation.

From the foregoing it will be seen that the invention is well adapted to attain all of the ends and objects hereinbefore set forth together with other advantages which are obvious and which are inherent to the structure.

As many possible embodiments may be made without departing from the scope of the invention, it is to be understood that all matter herein set forth or shown in the drawings is to be interpreted as illustrative and not in a limiting sense. It will also be understood that certain features and subcombinations are of utility and may be employed without reference to other features and subcombinations. This contemplated by and is within the scope of the claims.

Having thus described my invention, I claim:

1. In a device of the kind described, a rigid frame having a pair of laterally spaced side rails, a pair of axially aligned sleeves disposed between said rails and having laterally extending flanges slidably received on the rails whereby said sleeves are movable longitudinally thereof, the exterior of each sleeve tapering axially toward the other sleeve, a generally cylindrical core slidably received in the bore of each sleeve and having a tapered nose projecting beyond the sleeve and forming a continuation of the tapered exterior thereof, the tapered noses of the respective cores longitudinally splined and adapted to intermesh, a hydraulic ram mounted on said frame and connected to one of said cores for reciprocating the core axially, a thrust connection between said one core and its sleeve for causing the sleeve to move with the core when the latter travels toward the other core, a stop plate releasably secured to said rails for limiting the movement of said other core and its sleeve away from said one core, a plurality of telescoping links extending parallel to the axis of the sleeves from the flange of one sleeve to the flange of the other, said links adapted to contract as the distance between said flanges decreases, and means for at times locking said links in contracted condition to prevent axial separation of the sleeves.

2. A device as in claim 1 wherein the splines of one core are staggered circumferentially relative to the splines of the other whereby said cores intermesh upon movement of said one core toward the other.

3. In a device for installing on a pipe a rubber-like collar whose bore is smaller than the outside diameter of the pipe when the collar is in its normal unexpanded condition, a pair of co-axial generally conical members tapering toward one another, the smaller ends of said members adapted to enter opposite ends of the bore of said collar, means for advancing said members toward one another to cause the larger ends of same to enter the collar whereby the collar is expanded radially, each of said members comprising a core having a tapered nose forming said smaller end of the member and a co-axial sleeve having a tapered exterior forming a continuation of said nose, which continuation comprises said larger end of the member adapted to enter said collar upon said advance, a releasable connection between said two sleeves comprising cooperating elements on the respective sleeves forming a tension link therebetween and normally preventing the sleeves from moving apart when same have been advanced into said collar, said cores constructed and arranged in the sleeves to be removed therefrom when the

sleeves are thus connected whereby the collar is supported on and maintained in expanded condition by said sleeves alone, the bore of said sleeves being larger than said pipe whereby the pipe can be advanced therethrough when said cores have been removed, and means for releasing said connection thereby to permit said sleeves to move apart.

4. In a device for installing on a pipe a rubber-like collar whose bore is smaller than the outside diameter of the pipe when the collar is in its normal unexpanded condition, a pair of co-axial generally conical members tapering toward one another, the smaller ends of said members adapted to enter opposite ends of the bore of said collar, 15 means for advancing said members toward one another to cause the larger ends of same to enter the collar whereby the collar is expanded radially, each of said members comprising a generally cylindrical core having a tapered nose forming at the smaller end of said member and a co-axial sleeve having a tapered exterior forming a continuation of said nose, which continuation comprises said larger end of the member, each core comprising circumferentially spaced splines, the splines of one core being staggered circumferentially relative to the splines of the other core whereby said tapered noses are adapted to mesh and pass one another upon said advance and permit the adjacent ends of the two sleeves to 20 come into substantial abutment within the collar, annular flanges on the respective sleeves adapted to abut the ends of the collar and compress same axially as the adjacent ends of the sleeves approach one another, a telescoping connection between the two sleeves comprising co-acting elements on the respective flanges adapted to move relative to one another during the advance of the sleeves toward one another, means for locking 25 said elements against relative movement when the adjacent ends of the sleeves are in substantial abutment thereby to hold the sleeves together, and said cores constructed and arranged to be withdrawn from the bores of the sleeves when the sleeves are thus held together.

5. In a device for installing on a pipe a rubber-like collar whose bore is smaller than the outside diameter of the pipe when the collar is in its normal unexpanded condition, a pair of co-axial sleeves disposed in axially spaced relation, the bore of said sleeves being larger than said pipe, power operated means for advancing said sleeves axially toward one another until their ends substantially meet, means for expanding the collar radially as the sleeves approach one another and at the same time supporting the collar in axial alignment with the sleeves so the sleeves enter opposite ends of the enlarged bore of the collar, the exterior of each sleeve tapering axially toward the other sleeve whereby the advance of the sleeves into said collar causes the collar to continue to expand, an enclosed tube connected to one of said sleeves, a piston in the tube having a piston rod connected to the other sleeve whereby said piston travels through the tube during said advance of the sleeves toward one another, hydraulic fluid in the tube on both sides of the piston, a duct connecting the fluid space on one side of the piston with the fluid space on the other side whereby the fluid flows from one side of the piston to the other upon said travel of the piston, and valve means in said duct operable at will to close same and thus cause said tube and piston to resist movement of said sleeves relative to one another.

6. In a device for installing on a pipe a rubber-like collar whose bore is smaller than the outside diameter of the pipe when the collar is in its normal unexpanded condition, a pair of co-axial sleeves disposed in axially spaced relation the bore of said sleeve being larger than said pipe, power operated means for advancing said sleeves axially toward one another until their ends substantially meet, means for expanding the collar radially as the sleeves approach one another and at the same time supporting the collar in axial alignment with the sleeves so the sleeves enter opposite ends of the enlarged bore of the collar, the exterior of each sleeve tapering axially toward the other sleeve whereby the advance of the sleeves into said collar causes said collar to continue to expand, annular flanges on the respective sleeves adapted to engage opposite ends of the collar and compress the collar axially as the adjacent ends of the sleeves approach one another, a plurality of enclosed tubes secured to one of said flanges at circumferentially spaced intervals, said tubes paralleling the axis of said sleeves and each containing a piston having a piston rod connected to the other one of said flanges, hydraulic fluid in each tube on both sides of the piston, passageways through which fluid can flow from one side of the respective pistons to the other side during said movement of the sleeves, and valve means associated with said passageways operable to prevent said flow and thus cause said tubes and pistons to resist movement of said sleeves relative to one another.

7. In a device for installing on a pipe a rubber-like collar whose bore is smaller than the outside diameter of the pipe when the collar is in its normal unexpanded condition, a pair of axially aligned sleeves tapered toward each other adapted at times to enter opposite ends of the bore of said collar and hold same in expanded condition, each of said sleeves having a bore larger than the outside diameter of said pipe, an annular flange on each sleeve, rigid telescoping members having one end secured to the flange of one of said sleeves at circumferentially spaced intervals, the opposite ends of said telescoping members connected to the flange of the other sleeve, whereby said sleeves are movable axially toward and away from one another, and means operable at will to prevent said axial movement of the telescoping members.

8. A device as in claim 7 having a core removably insertable in the bore of each sleeve, each core having a tapered nose projecting from the associated sleeve and forming a continuation of the tapered exterior of the sleeve, means for immobilizing one of said sleeves and its core as a unit and simultaneously advancing the other sleeve and its core as a unit axially toward said first unit, the respective cores comprising circumferentially staggered splines whereby said tapered noses are adapted to pass one another upon said advance and permit the adjacent ends of the sleeves to come into substantial abutment.
